UNITED STATES PATENT OFFICE.

EARLE P. LEE, OF ROCHESTER, NEW YORK, ASSIGNOR TO NORTH EAST ELECTRIC COMPANY, OF ROCHESTER, NEW YORK, A CORPORATION OF NEW YORK.

IGNITION-COIL.

1,307,867.

Specification of Letters Patent. Patented June 24, 1919.

Application filed July 23, 1917. Serial No. 182,302.

To all whom it may concern:

Be it known that I, EARLE P. LEE, a citizen of the United States, residing at Rochester, in the county of Monroe and State of New York, have invented certain new and useful Improvements in Ignition-Coils; and I do hereby declare the following to be a full, clear, and exact description of the invention, such as will enable others skilled in the art to which it appertains to make and use the same.

This invention relates to an induction-coil suitable for use in producing the high-tension discharge used for ignition in internal-combustion engines.

Coils for the purpose in question are usually made with long straight cores of iron, upon which the primary and secondary windings are arranged concentrically, the primary winding being universally arranged within the secondary winding.

The arrangement of the windings as just described has been thought to be essential, owing partly to the requirements of thorough insulation of the secondary winding, and also to the fact that a primary winding located at any substantial distance from a core of the kind in question does not effectively magnetize the core, because of the large amount of magnetic leakage which takes place between the ends thereof within the space between the core and the winding.

Where an ignition-coil is energized by a constant source of current such as a secondary battery, the flow of current through the primary winding during normal operation of the apparatus is comparatively small, owing to the fact that it is interrupted at short intervals and is considerably reduced by inductance in the coil. In such an apparatus, however, if the coil remains in connection with the battery while the apparatus is not in operation, so that the primary winding is subjected continuously to the full E. M. F. of the battery, a much greater flow of current occurs, with a resultant heating effect in the coil which is liable to damage or destroy the coil. For this reason it is common to employ resistance-devices, automatic cut-outs and the like to avoid the danger of such a circuit-closure occurring while the apparatus is not in operation.

An object of the present invention is to produce an ignition-coil of such construction that it will sustain without injury a con-

tinuous heavy flow of current through the primary winding, so that the use, with such a coil, of external resistance-devices, automatic cut-outs and the like may be dispensed with. To this end it is proposed to reverse the usual arrangement of the primary and secondary windings, the secondary winding being placed next to the core, while the primary winding is arranged outside of the secondary winding so that it may be fully exposed to the cooling effect of the atmosphere or of adjacent bodies of heat-conductive material. In this way the coil is adapted to dissipate a comparatively large amount of energy in the form of heat without attaining a temperature which will be injurious to its structure.

The problem of suitably insulating a secondary winding arranged within a primary winding has been solved by the arrangement of parts hereinafter described, while it has been found that, by the use of a magnetic circuit of suitable character, the arrangement of the windings characteristic of the present invention may be employed without loss of efficiency in the coil, the essential point in this respect being the use of a magnetic circuit such that the lines of force external to the central core-member pass outside of the primary winding, and not between this winding and the central core-member.

Another object of the invention is to provide a simple and effective means for grounding one terminal of the secondary winding of the coil. To this end it is proposed to employ means including a pin which is thrust into the central core-member between the iron wires of which this member is composed.

A third object of the invention is to counteract the condenser effect which tends to occur between the primary and the secondary windings of the coil. To this end it is proposed to interconnect the primary and secondary windings through an air-gap, which is of sufficient length to prevent the flow of primary current, while short enough to prevent the accumulation of a static charge of any substantial tension in the primary and secondary windings.

The invention will be more fully set forth in the following description of the apparatus illustrated in the accompanying drawings, in which Figure 1 is a plan-view of an igni-

tion-coil embodying the present invention; Fig. 2 is a vertical section on the line 2—2 in Fig. 1; Fig. 3 is a horizontal section on the line 3—3 in Fig. 2; Fig. 4 is a side-elevation with the casing of the coil shown in section on the line 4—4 in Fig. 1; and Fig. 5 is a detail-view showing the means for grounding the secondary winding.

The invention is illustrated as embodied in an ignition-coil having a comparatively short, straight central core-member 10 consisting of parallel iron wires. Since the inverted arrangement of the windings characteristic of the present invention makes necessary a magnetic circuit of low reluctance, in order to secure a high degree of efficiency, the core-member 10 is combined with a yoke-member 11 in the form of a square ring, composed of iron wire wound continuously. This wire coil is held in suitable form at the corners by means of sheet-metal clips 12. The lower end of the core-member 10 is in direct engagement with the yoke-member, but as a slight air-gap in the magnetic circuit has been found to be desirable, a spacer 13 of insulating-material is interposed between the yoke-member and the core at the upper end of the latter.

The core is surrounded by a sleeve 14 of insulating-material, and upon this sleeve the secondary winding 15 is mounted directly. The successive layers of this winding are insulated from each other in the usual manner. The secondary winding is inclosed by three concentric sleeves of insulating-material 16, 17 and 18 respectively. The sleeves 17 and 18 are continuous, as shown in Fig. 3, while the sleeve 17 is interrupted at one point to produce a longitudinal slot 21. The primary winding 19 is wound upon the sleeve 18. In order to insulate the secondary winding thoroughly from the yoke-member 11, caps 20 of insulating-material are placed upon the ends of the coil, and the primary winding is wound from edge to edge of these caps, as shown in Fig. 2, being thus securely retained in place at its upper and lower extremities. The slot 21 is formed for the purpose of receiving the outer terminal of the secondary winding, this being the terminal which is connected with the spark-plugs of the engine. This terminal 22 extends upwardly through the slot 21, and is inclosed in a tube 23 of insulating material extending for some distance above the upper end of the coil. The terminal 22 is thus insulated from the primary winding by the combined thicknesses of the tube 23 and the sleeve 18.

Owing to the substantially closed magnetic circuit of the coil the casing in which it is inclosed may be made of metal, which has, among other advantages, that of readily carrying off heat generated in the coil. As illustrated the casing 24 is in the form of

a casting with an open top, which is covered by a cap 25 of molded insulating material. The various parts of the coil are held in their proper relative positions by means of a tie-rod 26, which passes axially through the central core-member 10. A plate 26 screwed to the lower end of the tie-rod bears against the bottom of the yoke-member 11, while a plate 28 and a nut 29, near the upper end of the rod, engage the upper surface of the yoke-member, thus holding the central core-member and the yoke-member securely in proper relation to each other. The lower end of the tie-rod passes through the bottom of the casing and is fixed by a nut 30, while the upper end passes through the cap 25, which latter is secured in place by a nut 31 on the end of the rod.

The cap is provided with a depending portion 32 perforated to receive the terminal 22 and its sheath, and a metallic insert 33 partially embedded in the cap constitutes a binding-post, being threaded to receive a nut 34 by which a high-tension conductor may be attached to the binding-post in the usual manner. As a convenient method of assembling the parts the binding post may be longitudinally perforated for the introduction of the terminal-wire 22, and after the cap 25 has been fixed in place the upper extremity 95 of the terminal-wire may be soldered in place in a recess at the upper end of the binding-post. The downward projection 32 increases the air-space and the surface which must be traversed by a high-tension discharge in passing from the terminal-wire to any adjacent metal part.

The primary terminals of the coil are attached to external conductors through binding-posts 35, molded in the cap 25, the terminal wires 36 being soldered, or otherwise secured, to these posts. The primary terminal-wires pass outwardly through channels formed in the insulating sleeve 17, and through perforations in the upper cap 20, as 110 shown in Fig. 2.

The inner terminal of the secondary winding is grounded as usual, and a feature of the invention resides in the simple and effective means employed for this purpose. A strip 37 of sheet-metal passes from the inner terminal of the winding to the lower end of the insulating sleeve 37, and is bent inwardly against the lower end of the core-member 10. A pin 38 is then driven through a hole in the sheet-metal and into the core between the wires thereof. For additional security the head of the pin may be soldered to the strip 37. The forcible engagement of the pin with the iron wires insures a reliable 125 metallic contact. The iron wires of the core are also in conductive engagement with the tie-rod 26, while the latter is in conductive engagement with the metal casing 24. The casing 24 is shown as provided with an inte- 130

gral flange 39 by which it may be secured in place upon any convenient part of the structure of the engine with which the ignition apparatus is employed, and in this way a 5 metallic conductive path or ground for the secondary current is provided through the pin 38, the core, the tie-rod 26 and the casing to the engine and thence to the spark-plugs.

It has been found that when an ignition- 10 coil is in operation an effect is produced in the coil similar to that of a condenser or Leyden jar, owing to the fact that the inner and outer masses of metal which constitute the primary and secondary windings are 15 separated by a thin layer or layers of dielectric material, so that they act like the plates of a condenser. This action interferes to some extent with the proper operation of the coil, and it has been found that a beneficial 20 result is obtained by interconnecting the primary winding and the grounded terminal of the secondary winding. Such connection is objectionable, however, where it is desired to employ a completely insulated primary circuit. A feature of the present invention resides 25 in the means for preventing an accumulation of static charges in the primary and secondary windings without grounding the primary circuit. This is accomplished, 30 as hereinbefore stated, by employing a connection between the primary and secondary windings which is interrupted by a slight air-gap. As shown in Fig. 2, this is arranged by providing one of the primary 35 binding-posts 35 with a projecting point 40 which nearly, but not quite, touches the nut 21 on the tie-rod. It will be seen that except for the air-gap between the point and the nut a short conductive path of low resistance 40 is afforded between the primary and secondary windings by way of the point 40, the tie-rod, the core, the pin 38 and the strip 37, and in this manner static charges are prevented 45 from accumulating except to the slight extent necessary to produce a discharge across the air-gap.

When a constant flow of current is produced through the primary winding 19 the heat generated in this winding is freely dissipated by radiation and convection, and 50 since the casing 24 may be made of metal or other material having high heat-conductivity, it affords little obstruction to the dissipation of this heat. Accordingly, the primary winding is prevented from attaining a 55

dangerous temperature, while the intervening insulating-material very effectually protects the secondary winding from the heat. The coil will, therefore, endure a continuous heavy flow of current without damage, and 60 the use of a resistance-device or an automatic cut-out is unnecessary, in so far as protection of the coil is concerned.

The invention is not limited to the embodiment thereof hereinbefore described and 65 illustrated in the accompanying drawings, but it may be embodied in various other forms within the scope of the following claims.

The invention claimed is:

1. An ignition-coil comprising a substantially closed core; a high-tension secondary winding upon the core; a low-tension primary winding arranged outside the secondary winding: a jacket of insulating-material, 70 between the said windings, spacing them apart and provided with a slot extending longitudinally; and an insulated conductor extending, from the outer terminal of the secondary winding, outwardly through said 75 slot.

2. An ignition-coil comprising a primary winding; a high-tension secondary winding; and a connection, between the primary winding and one terminal of the secondary winding, of a resistance high enough to prevent 80 substantial flow of primary current but low enough to permit the discharge of static charges between the two windings.

3. An ignition-coil comprising a primary 85 winding; a high-tension secondary winding; and a connection, between the primary winding and one terminal of the secondary winding, of high non-inductive resistance.

4. An ignition-coil comprising a primary 90 winding; a high-tension secondary winding; and a connection, between the primary winding and one terminal of the secondary winding, including an air-gap short enough to 95 permit the discharge, through said connection, of static charges between the said windings.

5. An ignition-coil having, in combination, a core of iron wires; a winding thereon; a strip of sheet-metal connected with a 100 terminal of said winding and lying over an end of said core; and a pin driven through 105 said sheet-metal and between the wires of the core.

EARLE P. LEE.
